UNITED STATES PATENT OFFICE.

FRITZ EDLUND, OF HOQUIAM, WASHINGTON.

DESIGN FOR A DISH-CONTAINER.

42,042.

Specification for Design.

Patented Dec. 26, 1911.

Application filed September 25, 1911. Serial No. 651,568. Term of patent 7 years.

To all whom it may concern:

Be it known that I, FRITZ EDLUND, a citizen of the United States, residing at Hoquiam, in the county of Chehalis and State of Washington, have invented a new, original, and ornamental Design for Dish-Containers, of which the following is a specification, reference being had to the accompanying drawing, forming a part thereof, in which the figure is a perspective view of a dish container.

I claim:

The ornamental design for a dish container as shown.

FRITZ EDLUND.

Witnesses:

J. B. LUCAS,
N. LIND.
